US00D701166S

(12) **United States Design Patent**
Fishman et al.

(10) **Patent No.:** **US D701,166 S**
(45) **Date of Patent:** **** Mar. 18, 2014**

(54) **BATTERY ASSEMBLY**

(75) Inventors: **Elliot G. Fishman**, Pittsburgh, PA (US);
Martin David Smale, Parma, OH (US);
Ryan J. Wayne, Brecksville, OH (US);
Jonathan Andrew Taylor, Houston, PA (US)

(73) Assignee: **GrafTech International Holdings Inc.**, Parma, OH (US)

(**) Term: **14 Years**

(21) Appl. No.: **29/403,092**

(22) Filed: **Sep. 30, 2011**

(51) LOC (10) Cl. **13-02**

(52) U.S. Cl.

USPC **D13/103; D13/119**

(58) **Field of Classification Search**

USPC D13/102–106, 110, 118–119, 184;
429/96–100, 149, 163, 187

See application file for complete search history.
